(57) **CLAIM**

The ornamental design for an infrared sensor lens as shown and described.

DESCRIPTION

FIG. 1 is an isometric view of my new infrared sensor lens showing my new design with environmental structure;

FIG. 2 is an isometric view thereof;

FIG. 3 is a top plan view thereof; and,

FIG. 4 is a front elevation view thereof, with the rear, right side, and left side views being identical.

The broken dash lines shown in FIG. 1 are for illustrative purposes only and represent non-claimed environmental structure. Neither the portions of the environmental structure shown in broken dash line nor the broken dash lines themselves form any part of the claimed design.

1 Claim, 3 Drawing Sheets
